[57] CLAIM

The ornamental design for a combined locomotive console and master controller cover, as shown and described.

DESCRIPTION

FIG. 1 is a front elevation view of a combined locomotive console and master controller cover showing our new design;

FIG. 2 is a top plan view thereof;

FIG. 3 is a left side elevation view thereof;

FIG. 4 is a right side elevation view thereof;

FIG. 5 is a rear elevation view thereof;

FIG. 6 is a bottom plan view thereof;

FIG. 7 is a front elevation view of a combined locomotive console and master controller cover showing a second embodiment of our new design;

FIG. 8 is a top plan view of FIG. 7;

FIG. 9 is a left side elevation view of FIG. 7;

FIG. 10 is a right side elevation view of FIG. 7;

FIG. 11 is a bottom plan view of FIG. 7.

The rear of the second embodiment of the combined locomotive console and master controller cover is the same as the first embodiment shown in FIG. 5.

The broken lines in the drawing are for illustrative purposes only and form no part of the claimed design.
